J. J. HINES,
PROJECTILE.

Patented Dec. 24, 1918.

John J. Hines, Inventor
By James Sheehan & Co., Attorneys.

UNITED STATES PATENT OFFICE.

JOHN J. HINES, OF HALIFAX, NOVA SCOTIA, CANADA.

PROJECTILE.

1,288,839.

Specification of Letters Patent. Patented Dec. 24, 1918.

Application filed July 16, 1917. Serial No. 180,794.

To all whom it may concern:

Be it known that I, JOHN J. HINES, a citizen of the Dominion of Canada, residing at Halifax, in the Province of Nova Scotia and 5 Dominion of Canada, have invented new and useful Improvements in Projectiles, of which the following is a specification.

My present invention pertains to projectiles; and it has for its general object to provide a projectile embodying reliable means for assuring the explosion of the projectile irrespective of whether it lands in the water or brings up against an obstruction.

A secondary object of the invention is the 15 provision in a projectile of improved means for locking the firing pin with a view to precluding a premature explosion; the said means being constructed and arranged to be actuated by centrifugal motion of the projectile incidental to its flight through the air, and being combined with means for fastening it out of engagement with the firing pin after it is once withdrawn from the same so as to contribute to the explosion of the projectile when it enters water or strikes a vessel or other obstacle in its path.

Other objects and practical advantages of the invention will be fully understood from the following description and claims when 30 the same are read in connection with the drawings, accompanying and forming part of this specification, in which:

Figure 1 is a side elevation of the projectile constituting the preferred embodiment 35 of my invention.

Fig. 2 is an enlarged, broken longitudinal-central section of the shell, or projectile.

Fig. 3 is a fragmentary section, taken in 40 the same plane as Fig. 2 and illustrating the position the locking means for the firing pin assumes and in which it is secured incidental to the flight of the projectile through the air.

Similar numerals of reference designate corresponding parts in all of the views of 45 the drawings.

The hollow body 1 of my novel projectile is designed to carry a suitable explosive charge and is equipped with the usual exterior band 2 for the engagement of the lands 50 of a rifle so that the projectile will be rotated about its axis during its flight from the rifle to the objective. In its rear end the body 1 is provided with a filling aperture 3 and a vent aperture 4, normally closed by 55 plugs 5 and 6, respectively.

A comparatively large aperture is provided in the forward end of the body 1, and is closed by a plug 7, hereinafter referred to in detail.

Suitably fixed to and arranged within the body 1 is a cylindrical portion 8, open at 9 to the interior of the body, and provided with a lining 10, of brass or other suitable material. The chamber 11 in the rear portions of the cylinder 8 and lining 10 is 65 adapted to contain a primer; and it will also be noted that a chamber 11^a is provided in the forward portion of the lining 10 and in front of the body portion 8.

Formed in the body 1 are four (more or 70 less) openings 19 which are in registration with apertures 20 in the lining 10 and are designed when the projectile enters a body of water to conduct water to the said chamber 11^a.

At 14 in the lined cylinder is a diaphragm, preferably of rubber or rubber composition, and back of said diaphragm is a detonator 13 or other suitable means which when struck by the firing pin will serve to fire the primer 80 in chamber 11 and through said primer explode the charge in the hollow body 1. Opposed to the forward side of the said diaphragm is a spring 14^a, and in front of said spring is a piston 15, equipped with a gasket 16. The piston 15 is integral with or otherwise fixed to the firing pin 17, and the said pin is provided with the preferably stepped enlargement 18.

For the purpose of normally holding the 90 firing pin away from the detonator 13, I provide the radially-movable latch 21, backed by the spring 22, and in order to retain the said latch 21 out of engagement with the enlargement 18, Fig. 3, I provide 95 the movable retainer 23, backed by the spring 24.

At 25 the plug 7 is chambered, and secured by a fine thread in said chamber is a plug 26 which is preferably of steel so as to 100 serve as a striking plug and is provided with a rear extension aligned with the firing pin 17.

The spring 14^a may be of any desired tension according to the depth in the water at which it is desired to explode the projectile.

In operation the projectile is fired from a suitably elevated piece of ordnance, and during its flight through the air the rotation of the projectile about its axis will throw the latch 21 outwardly, against the action 110

of the spring 22, and thereby release the firing pin 17, and when the latch is so thrown outwardly the retainer 23 will assume a position between the latch and the firing pin, 5 Fig. 3, and in that way effectually prevent the latch from interfering with the subsequent movement of the firing pin.

If the projectile lands in the water, which it will enter point first because of the forward portion of the projectile being comparatively heavy, the water entering through the four (more or less) openings 19 will occupy the chamber 11^a and either alone or in combination with some chemical adapted to 15 expand under the action of water will act against and force the piston rearwardly and thereby cause the pin 17 to strike the cap and explode the charge in the projectile.

If, on the other hand, the projectile brings 20 up against an obstruction, the striking plug 26 will be forced rearwardly by the stripping of its fine thread and in consequence its stem 27 will force the firing pin 17 rearwardly and bring about the explosion of the 25 charge.

The primer referred to as being designed to be placed in the chamber 11 will preferably be in the form of a high explosive.

Having described my invention, what I 30 claim and desire to secure by Letters Patent, is:

1. The combination in a projectile, of a body, a movable firing pin arranged therein and having a stepped enlargement, a latch 35 movable rectilinearly in a radial direction in the body by centrifugal force due to rotation of the body about its axis and constructed and arranged at its inner end to engage the stepped enlargement of the firing pin 40 and normally hold said firing pin against movement, and a spring-pressed retainer movable rectilinearly at right angles to the latch and adapted when the latch is moved endwise outwardly to assume a position in 45 front of the latch and hold the same out of

engagement with the stepped enlargement of the firing pin.

2. The combination in a projectile, of a body, a movable firing pin therein equipped with a piston, means constructed and arranged when the projectile enters a body of water to enter the projectile and cause firing movement of the firing pin, a striking plug secured by weak means in the nose of the body and adapted on impact to be forced 50 rearwardly in the body and to force the firing pin in the same direction, a latch movable in the body by centrifugal motion thereof and constructed and arranged to normally hold the firing pin against movement, 55 and retaining means constructed and arranged when the latch is disengaged from the firing pin to hold the latch out of engagement with said pin.

3. A projectile having a piston cylinder, 65 a diaphragm interposed between said cylinder and the interior of the projectile, a piston movable in the cylinder, a firing device movable with the piston, a cap at the opposite side of the diaphragm, with reference 70 to the firing device, and means for enabling water to enter the piston cylinder when the projectile enters a body of water.

4. A projectile having a piston cylinder, a diaphragm interposed between said cylinder 75 and the interior of the projectile, a piston movable in the cylinder, a spring interposed between the diaphragm and the piston, a firing device movable with the piston, a cap at the opposite side of the diaphragm, with reference 80 to the firing device, and means for enabling water to enter the piston cylinder when the projectile enters a body of water.

In testimony whereof I have hereunto set my hand in presence of two subscribing witnesses. 85

JOHN J. HINES.
